UNITED STATES PATENT OFFICE

ORVILLE D. EARON, OF MONTCLAIR, NEW JERSEY, ASSIGNOR TO THE HARDRIGHT COMPANY, A CORPORATION OF NEW JERSEY

DESIGN FOR A BRUSH HANDLE OR THE LIKE

Application filed February 15, 1930. Serial No. 34,559. Term of patent 14 years.

To all whom it may concern:

Be it known that I, ORVILLE D. EARON, a citizen of the United States, residing at Montclair, county of Essex, and State of New Jersey, have invented a new, original, and ornamental Design for Brush Handle or the like, of which the following is a specification, reference being had to the accompanying drawing, forming part thereof, wherein:

Fig. 1 is a perspective view of a preferred embodiment of the design;

Fig. 2 is a top view of the design as of Fig. 1; and

Fig. 3 is a side view of the same.

I claim:

The ornamental design for a brush handle or the like substantially as shown.

ORVILLE D. EARON.
